UNITED STATES PATENT OFFICE.

ALVIN O. HALL, OF NEW YORK, N. Y.

INKING-RIBBON ALARM FOR TYPE-WRITING MACHINES.

SPECIFICATION forming part of Letters Patent No. 314,016, dated March 17, 1885.

Application filed March 24, 1884. (No model.)

To all whom it may concern:

Be it known that I, ALVIN O. HALL, of New York city, county and State of New York, have invented certain new and useful Improvements in Inking-Ribbon Alarms for Type-Writing Machines, of which the following is a full, clear, and exact description, reference being had to the accompanying drawings, and to the letters of reference marked thereon.

My invention is especially applicable in connection with inking-ribbons employed upon type-writing machines, and its object is to provide a simple and cheap appliance whereby an alarm or other indicating mechanism may be operated in connection with an inking-ribbon and be automatically actuated or released when the ribbon reaches or approaches its limit of travel. By my improvements I supply an alarm which will warn the operator to shift the ribbon-feeding mechanism; and the said improvements involve certain novel and useful arrangements of parts, as will be hereinafter set forth and claimed.

In the accompanying drawings, forming part of this specification, Figure 1 is a front elevation, Fig. 2 a top or plan view, and Fig. 3 an end elevation, illustrating an appliance or arrangement adapted to operate in accordance with my invention, the writing mechanism being omitted as not being essential to the illustration. Figs. 4, 5, and 6 are side elevations showing various forms which may be given the tripping appliance, which is connected with the ribbon, these figures being on a larger scale than the others.

In all these figures like letters of reference, wherever they occur, indicate corresponding parts.

A represents the inking-ribbon, which is wound upon and unwound from the spools B B at either side of the type-writer, and thus made to traverse the machine from left to right or from right to left, accordingly as the feeding mechanism is adjusted.

C C are the ordinary flexible end pieces with which the ribbon is usually connected; but these may be omitted and the ribbon applied directly to the spools. At suitable points upon these pieces or upon the ribbon I affix lugs or projections a a, or equivalent devices arranged to

lift or otherwise permit the movement of a slight wire or other arm, as D, the same being suitably connected with any convenient part of the frame of the machine. The lifting or movement of this wire causes the indicator to be released or actuated. The indicator may be arranged to appeal to the eye or to the ear.

At E is a light flap of metal or other material, hinged to a convenient support at its base, and having its upper end supported, as by a projection, b, upon the wire or arm D. When the support is removed, this flap drops down within sight of the operator and will at once warn him of the position of the inking-ribbon. This method is preferred to the ringing of a bell, for the reason that it is not desirable to add to the number of bells already employed in or on the type-writer, but the bell-ringing arrangement is very simple and is within the scope of my invention. Fig. 3 shows one manner in which it may be arranged, in which figure c represents the bell, and d its striker. The latter is released as soon as the flap drops down, in a manner which will be readily understood.

The lug or tripper connected with the ribbon may be of any form, and when projecting to any considerable extent from the surface of the ribbon the spool may be provided with a cavity, as at e, for accommodation of the lug, so as not to interfere with the smooth winding of the ribbon. In Fig. 6 the tripper is shown as composed of two parts, one hinged upon the other, and provided with a simple stop, f, the purpose of which is to sustain one of the parts when they are free to be opened. This form is folded up as the ribbon is wound and will not occupy too great space, even without a cavity in the spool for its reception.

The tripper may be of a variety of forms, and may be connected with the ribbon (or with the end pieces) in any manner.

The arrangement above indicated has been found in practice to admirably answer the purposes or object of the invention as previously set forth; but I do not desire to be understood as limiting myself to any specific devices herein shown. Different patterns of machines may require slightly different arrangements or locations of parts.

In Fig. 1 the ribbon is shown as wound upon the spool at the left so far as to bring the

tripper at the right in contact with the bar or arm D. Further movement of the ribbon will cause the raising of the bar and the movement of the alarm. The operator is thus notified 5 that he should shift his feeding appliances in such manner as to wind the ribbon on the spool at the right, and when it is sufficiently wound thereon the tripper upon the other side will be brought into position to actuate the 10 alarm, and so on as the ribbon travels in one direction or the other.

Having now fully described my invention, what I claim as new, and desire to secure by Letters Patent, is—

15 1. In combination with an inking-ribbon of a type-writer, a suitable tripping device, substantially as described, and an alarm mechan-

ism, substantially as described, arranged to be released through the medium of said tripping device, substantially as and for the purpose set forth. 20

2. The inking-ribbon, the trippers applied in connection therewith, the movable bar or arm, and an alarm mechanism, substantially as described, arranged and combined substantially as and for the purposes set forth. 25

In testimony that I claim the foregoing I have hereunto set my hand in the presence of two witnesses.

ALVIN O. HALL.
